Soopyk Water Dispenser with Ice Maker, amazon.ca, First available date Mar. 24, 2025. Retrieved from the internet Jun. 26, 2025<<https://www.amazon.ca/SOOPYK-Self-Cleaning-Bottom-Dispenser-Capacity/dp/B0F292TKZ3> (Year: 2025).*

Primary Examiner — Joseph Kukella*Assistant Examiner* — Darryl J Dardenne(74) *Attorney, Agent, or Firm* — Daniel M. Cohn;
Howard M. Cohn(57) **CLAIM**

The ornamental design for a water dispenser with ice maker as shown and described.

DESCRIPTION

FIG. 1 is a perspective view of a water dispenser with ice maker showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash-dash broken lines in the drawings depict portions of the water dispenser with ice maker that form no part of the claimed design.
